Patented Oct. 17, 1911.

UNITED STATES PATENT OFFICE.

ERNEST D. MAXWELL, OF CLIFTON FORGE, VIRGINIA.

PNEUMATIC SEPARATOR.

1,006,249.

Specification of Letters Patent. Patented Oct. 17, 1911.

Application filed December 3, 1910. Serial No. 595,526.

To all whom it may concern:

Be it known that I, ERNEST D. MAXWELL, a citizen of the United States, residing at Clifton Forge, in the county of Alleghany 5 and State of Virginia, have invented a new and useful Pneumatic Separator, of which the following is a specification.

This invention has relation to pneumatic separators and cleaners and consists in the 10 novel construction and arrangement of its parts as hereinafter shown and described.

The object of the invention is to provide a simple and an effective cleaner of the character indicated which is adapted to separate 15 fibrous material from seed or stones, sprouts from grain and at the same time to clean or scour deleterious material from the superior material which is separated from the inferior material.

20 With the above object in view, the apparatus includes a perforated table which is mounted for rotation and upon which the mixed material is placed. A strip of porous flexible material may be placed upon the 25 upper surface of the said table. Adjustable suction trunks are arranged in pairs and the members of each pair are located one above and one below the said table equi-distant apart and tangentially within and to the periphery of the table and relatively close to 30 each other and to the table and a brush is journaled adjacent each trunk that is located above the table. An air blast means is also located in each suction trunk that 35 is above the table and the said suction trunks and brushes extend at acute angles to the diameter or tangentially within and to the periphery of the table.

Figure 1 is a vertical section through the 40 machine showing one side thereof, and the position of the operating parts of the machine. Fig. 2 is a top plan view of the machine. Fig. 3 is an enlarged view in top plan, of a portion of the table and the 45 brushing and cleaning mechanism. Fig. 4 is a cross section through the table, pneumatic cleaners and the brush.

The apparatus consists of a perforated table 1 which is mounted upon a vertically 50 disposed shaft 2. Any suitable means may be provided for rotating the said shaft and

table. The table 1 is preferably surrounded at its edge by an upstanding flange 3 which may be of any desired height and over which mixed material may be fed upon the 55 upper surface of the said table 1. The cleaning and separating devices which co-operate with the said table are arranged in groups or units and as the said devices are similar in all of the groups a description 60 of each individual device in each group will answer for all. Each group of cleaning devices includes a suction trunk 4 which is located below the table 1 and which is adjustably mounted upon an elbow 5 which 65 in turn is adjustably connected with a suction pipe 6. A suction trunk 7 is located above the surface of the table 1 and above the suction trunk 4 and the said suction trunk 7 is adjustably connected with a suc- 70 tion pipe 8.

Any suitable means may be provided for creating suction through the pipes 6 and 8 and suction trunks 4 and 7 and as illustrated in Fig. 1 of the drawings, such a device 75 consists of a fan 9 located in a casing 10 which is provided with a discharge pipe 11. The said discharge pipe 11 is continued into branches 12 and 13 the branch 12 connecting with the pipe 8 and the branch 13 connecting with the pipe 6. The said branches 12 and 13 are provided with valves 14 and 15 respectively and it will be seen that when the fan 9 is in operation a blast will be discharged through the pipe 11 and pipes 85 12 and 13 into the pipes 8 and 6. This blast passing through the said pipes 8 and 6 will create a vacuum at the ends of the said pipes 6 and 8 which connect with the suction trunks 7 and 4 and consequently vacuums will be created in said suction trunks. The inlet 16 into the suction trunk 7 is spaced slightly above the upper surface of the table 1 while the upper opening into the suction trunk 4 is closed by the said table 1. 95 If desired a strip of porous flexible material 17 may be placed upon the upper surface of the table 1 and the said strip may extend under the inlet openings 16 into the suction trunk 7 of the entire series of cleaners. Blast pipes 18 extend over the table 100 1 and are provided with discharge nozzles

19, one of the said nozzles being located immediately over each of the suction trunks 7. Rotating brushes 20 are also located above the table 1 and a brush 20 is located 5 adjacent the end of each suction trunk 7.

Any suitable means may be provided for 10 rotating the brushes 20. The suction trunks 4 and 7 are elongated and their long dimensions are pitched at acute angles to the diameter of the table 1. The cleaning devices hereinbefore described are preferably 15 six in number arranged at regular intervals at the periphery of the table 1.

In operation the table 1 is maintained in 20 a state of rotation and a suction draft is created through the trunks 4 and 7 in any suitable manner or the manner as hereinbefore described. At the same time blasts of air are forced through the pipes 18 and 25 nozzles 19 and the brushes 20 are maintained in a state of rotation. The trunks 4 and 7 may be adjusted in position with relation to each other and may be adjusted with relation to the center of the table 1. The material to be separated is passed in mixed condition upon the upper surface of the table 1 and the said material is first brought in contact with the brush 20 of the initial set of cleaners. The said brush 20 will engage the 30 material and have a tendency to pass the heavier or bulkier particles of material over the top of the trunk 7 and toward the brush 20 of the next group of cleaners. At the same time the finer particles of material are 35 sucked down through the perforations of the table 1 into the trunk 4 and through the elbow 5 and pipe 6 and away from the apparatus. At the same time particles of material borne upon the draft of air which 40 passes down through the perforations in the table 1 in the trunk 4 are sucked up again through other perforations in the said table 1 into the trunk 7 in the manner as indicated in Fig. 1 of the drawing. At the same time 45 particles of material are sucked under the edge of the trunk 7 and up through the inlet 16 therein into the interior of the said trunk and the particles thus received within the trunk are carried through the pipe 8 away from the apparatus. At the same time the 50 blast of air discharged from the nozzle 19 engages the heavier particles of material which are passed up by the brush 20 and the said blast assists in carrying the heavier 55 particles over the top of the trunk 7 and toward the brush 20 of the next group of cleaners. This operation is repeated throughout the entire series of cleaners. In this manner the lint may be removed from 60 cotton seed, or fiber may be removed from other solid bodies the parts of the apparatus being so adjusted that the seed will remain upon the table top 1 while the lint is drawn under the trunk 7 or into the trunk or the

fine particles of deleterious material may be 65 drawn into either one of the said trunks when the lint is drawn into the other.

As illustrated in Fig. 3 of the drawing, the final trunk 7 of the series of trunks may be provided at its edge with the teeth as at 70 21. When the apparatus is used for removing lint from cotton seed, the seed cotton is carried successively over the trunks 7 and at the edge of each trunk 7 some of the lint is removed from the seed, when however the 75 seed arrives at the final trunk 7 under the series in which the trunk is provided with the teeth 21 the said seed engage the teeth and the shorter particles of lint are torn from the seed and carried under the said 80 trunk 7 and when the seed are thus shorn they are passed up along the top of the final trunk 7. Therefore it will be seen that with an apparatus as described, the longer lint is removed from the seed at the first trunk 7 85 and successively throughout the remaining trunks the lint is gradually shorter, therefore the lint may be collected in different grades as it is removed from the seed. When a strip of flexible material 17 is used upon 90 the top of the table 1, the said strip will have a tendency to increase the frictional resistance to the material and prevent the same from passing too rapidly over the top of the table to accomplish the separation of the 95 different parts as indicated. By adjusting the trunks 4 and 7 with relation to each other the draft strains or pulls upon the material being separated may be exercised upon the said material in varying directions, that 100 is to say, the said strains may be more or less in a vertical direction or more or less in a horizontal direction, and thus the parts may be adjusted in order to facilitate the separation of the parts of the material. 105 Again by adjusting the valves 14 and 15 the suction draft through the trunks 4 and 7 may be increased or diminished or the proportions of the intensity of draft through the said trunks may be regulated with relation to each other. That is to say there may be greater suction draft through the trunk 7 than through the trunk 4 and vice versa. The apparatus hereinbefore described may also be used for bleaching, heating or drying 115 material. When it is used for bleaching material the bleaching element or fluid is forced through the pipes 18 and sprayed into the material through the nozzles 19. When the apparatus is used for heating or drying material warm air is forced through the said pipe 18 and is discharged into the material 120 through the nozzle 19.

Having described the invention what I claim as new and desire to secure by Letters Patent is:

1. An apparatus of the character indicated comprising a perforated movable disk,

suction trunks arranged in pairs and located at the opposite sides of said support, said pairs of trunks being disposed tangentially of the periphery of the support, and means 5 for creating suction draft through said suction trunks.

2. An apparatus of the character indicated comprising a perforated movable material supporting disk, suction trunks 10 justably located at the opposite sides of the said disk and tangentially within the periphery of said disk, and means for creating suction draft through the said trunks.

3. An apparatus of the character indicated comprising a movable perforated supporting disk, a perforated flexible material located upon the top of the supporting disk, suction trunks located at the opposite sides of the said supporting disk, and tangentially 20 to the periphery thereof, and means for creating suction draft through the said trunks.

4. An apparatus of the character indicated comprising a circular perforated table 25 mounted for rotation, suction trunks located at the opposite sides of the said table, said trunks being elongated and having their longer dimensions obliquely disposed with relation to the diameter of the table, and 30 means for creating suction draft through the said suction trunks.

5. An apparatus of the character indicated comprising a movable perforated material support, suction trunks located at the 35 opposite sides of the said support, means for discharging fluid under pressure over the uppermost trunks, and means for creating suction draft through the said trunks.

6. An apparatus of the character indicated comprising a movable perforated material support, suction trunks located at the 40 opposite sides of said support, means for creating suction draft through the said trunks, a brush journaled for rotation above 45 the said material support and adapted to engage material and direct the same over the uppermost suction trunk.

7. An apparatus of the character indicated comprising a perforated movable material support, suction trunks located at the 50 opposite sides of said support, means for creating suction draft through said trunks, means for discharging fluid under pressure over the uppermost suction trunk, a brush journaled for rotation above the material 55 support and adapted to engage material and direct the same over the uppermost suction trunk.

8. An apparatus of the character indicated comprising a circular perforated table journaled for rotation, a series of 60 cleaning and separating devices arranged to coöperate with said table, each group of the said cleaning and separating devices con-

sisting of suction trunks located at the opposite sides of the table, means for delivering fluid under pressure over the uppermost suction trunk, movable brushes for engaging the material and directing the same over the uppermost suction trunk, the group of 65 70 cleaning and separating devices being so arranged about the table that the material which is passed over the uppermost suction trunk of one group is delivered to the edge portion of the uppermost suction trunk of 75 the next group of cleaning and separating devices.

9. An apparatus of the character indicated comprising opposed suction trunks and being in advance of the other, and a perforated movable circular support located between the trunks, said trunks being arranged circumferentially and tangentially 80 to the support.

10. In an apparatus of this character, a 85 rotatably mounted circular perforated table, and two series of suction devices arranged at equi-distances apart and tangentially within the periphery of the table, one series of said devices being arranged to operate 90 above and the other series below the table.

11. In an apparatus of this character, a rotatably mounted circular perforated table, and a series of pairs of suction devices arranged at equi-distances apart and tangentially 95 within the periphery of the table, said table passing between the respective members of each pair of suction devices.

12. In an apparatus of this character, a rotatably mounted circular perforated table, 100 a series of upper and lower cleaning devices between which the table passes, and disposed equi-distantly apart and within the periphery of the table, and means for adjusting said devices with relation to the table and 105 in relation to each other.

13. In an apparatus of this character, a rotatably mounted circular perforated table, an upper series of cleaning devices disposed 110 above and tangentially to the periphery of the table, and a lower series of cleaning devices disposed below the table.

14. In an apparatus of this character, a rotatably mounted circular perforated table, a stationary rim therefor, a series of cleaning devices mounted in the rim and disposed above the table and equi-distances apart, and a series of co-acting cleaning devices mounted 115 below the table.

15. In an apparatus of this character, a rotatably mounted circular perforated table, a stationary rim therefor, a series of suction trunks carried by the rim and disposed above and tangentially to the periphery of the table, and a series of co-acting suction 120 125 trunks disposed below the table.

16. In an apparatus of this character, a rotatably mounted circular perforated table,

a stationary rim therefor, a series of suction trunks carried by the rim and disposed above said table, a brush opposed to each trunk, and a series of suction trunks below 5 the table and in substantially the same position relatively to the table as the series of suction trunks above the table.

In testimony that I claim the foregoing as my own, I have hereto affixed my signature in the presence of two witnesses.

ERNEST D. MAXWELL.
